[57] ABSTRACT

Earth auger pilot bit is an improvement upon U.S. Pat. No. 2,773,673. The body of the bit is triangular when viewed in side elevation from one direction and narrower and thinner when viewed turned 90°. There is a "fish-tail" lower extremity. There are two (or more) spiral cutting blades protruding from the body and extending into the fishtail, the second blade on each side joining the leading blade of the other at the bottom of the bit to reinforce same. The improvement consists of having one or more reinforcing ribs supplementing and reinforcing the fishtail and also the leading spiral blades. The reinforcing ribs resist fracture of the bit upon severe impact and absorb wear, thereby prolonging the life of the bit.

PILOT BIT WITH REINFORCING RIBS

This invention relates to a new and improved pilot bit having one or more reinforcing ribs on each of the blades which protrude from the body of the bit. The pilot bit for earth augers shown in U.S. Pat. No. 2,773,673 has enjoyed wide-spread commercial success. One of the problems encountered in use of such bit has been that when the bit is subjected to the impact of contact with hard rock the points of the "fish-tail" extremities tend to break, and the action of the pilot bit is accordingly adversely affected. Another problem encountered in use of the bit in extremely abrasive soil is the fact that the blade which projects from a generally conical body wears with the passage of time and the action is similarly impaired.

The principal purpose of the present invention is to avoid these problems which have heretofore been encountered. Accordingly, a principal object of the present invention is to provide reinforcing ribs for each of the blades of the bit of a spiral configuration hereinafter described.

Another principal feature of the present invention is to resist more effectively the impact which tends to break off the points of the fish-tail extremities of the pilot bit.

An optional feature of the invention is the formation of the ribs by application of hard metal, such as metal welded thereon or applied by hard facing. The hard ribs enhance the life of the bit.

A further feature of the use of ribs is the fact that as wear occurs the body of the bit wears away between ribs, resulting in fingers of metal protruding from the cutting edges of the bit. Such fingers improve the drilling action of the bit, and this feature is further enhanced if the ribs are of harder metal than the body of the bit.

In addition to the foregoing principal advantages of the invention, the present bit has the advantages of U.S. Pat. No. 2,773,673. More specifically, one of the features of the invention is that the bit breaks the earth effectively and also diverts the spoil broken by the bit laterally and upwardly away from the center of the hole being bored so that the main auger may effectively convey the spoil.

Another feature of this invention, as in the previous patent, is the self-sharpening features of the cutting extremity or fishtail of the bit.

Still another feature of the invention is that the principal component of the stress imposed upon the blades of the bit are in compression rather than shear and hence the stress on the blades is diminished.

Other objects of the present invention will become apparent upon reading the following specification and referring to the accompanying drawings in which similar characters of reference represent corresponding parts in each of the several views.

In the drawings:

FIG. 1 is a side elevational view of the pilot bit in accordance with the present invention.

FIG. 2 is a top plan as viewed on line 2-2 of FIG. 1.

FIG. 3 is a bottom plan view thereof.

FIG. 4 is a side elevational view taken 90° from FIG. 1 as indicated by line 4-4 of FIG. 1.

FIG. 5 is a view similar to FIG. 1 of a modified bit.

FIG. 6 is a view similar to FIG. 3 of said modification.

FIG. 7 is a vertical sectional view of said modification taken substantially along line 7-7 of FIG. 6.

FIG. 8 is a fragmentary sectional view through a rib as exemplified by section 8-8 of FIG. 5.

FIG. 9 is a view similar to FIG. 5 of another modified bit.

FIG. 10 is a view similar to FIG. 6 of the modification of FIG. 9.

FIG. 11 is a side elevational view of said modification rotated 90° from the position of FIG. 9.

The pilot bit of the present invention is a unitary casting having an upper body portion 11 which merges into a lower "fish-tail" extremity 12. The upper body 11 viewed in the direction of FIG. 1 is an inverted triangle having about a 90° included angle. As viewed turned 90° in FIG. 4, the body 11 is flat rather than triangular.

15 The upper end 13 of the bit is flat and its plane is perpendicular to the axis 14 of the cone, which is also the axis of rotation of the bit, and its axis of symmetry. Top 13 resembles a parallelogram. (FIG. 2) Extending into upper end 13 is a socket 16 which receives a drive lug (not shown) connected to an auger shaft. The construction of socket 16 is shown in U.S. Pat. No. 2,870,995 and is not here detailed. In order to provide room for socket 16, bosses 17 are formed on opposite sides of the upper body 11 extending down from upper 20 end 13 and terminating in diametrically opposed, horizontal shoulders 18. Flats 19 are formed on the body and extending diametrically through the body between flats 19 and into the lower portion of recess 16 are holes 21. A bolt passes through the holes and also through an apertured extension (not shown) of the drive lug to secure the pilot bit to said lug.

25 Only one side of the bit will be described since the opposite side is identical.

30 Blade 26 is formed protruding from upper end 13 and originates at acute outside corner 27 of the parallelogram upper end 13. The outer edge 28 of blade 26 curves downwardly-forwardly in the direction of rotation of the bit (counter-clockwise as viewed in FIG. 3).

35 The length of blade 26, as viewed in plan, is approximately 180° of arc. In elevation, the blade extends below the theoretical apex of the conical body to provide the "fish-tail" 29 which is characteristic of U.S. Pat. No. 2,773,673. The fish-tail 29 is approximately 40 percent of the total vertical height of the bit. The extent 40 to which the blade extends beyond the outline of the triangular body 11 increases as the blade proceeds downward. That is, at the upper corner 27 the blade outer edge and the body are co-extensive, but as the blade proceeds downwardly the dimension by which the outer edge 28 thereof protrudes beyond the theoretical triangular shape of the body increases steadily.

45 In cross-section, blade 26 comes to a rather blunt point at its outer edge 28 and front and back flanks 31, 32 slant toward the body at an angle of about 30° and merge with the body on front and back flanks 31, 32 in a radius 33. This form of cross-section of the blade gives strength to the blade and also directs the spoil cut by the bit outwardly and upwardly away from axis 14 so that the auger above the pilot bit can handle the 50 spoil.

55 At the lower end of the leading edge of blade 26, the latter is truncated in an approximately horizontal cutting edge 34 which is displaced forwardly of a radius from axis 14 in the direction of the turning of the bit. The outer corner 36 of the cutting edge is positioned 60 on a diameter. The inner edge 37 of the fish-tail slants

65

downwardly-inwardly at an angle of about 45° with respect to axis 14.

The foregoing description of the outer edge 28 of blade 26 is substantially the same as the blade of U.S. Pat. No. 2,773,673.

A feature of FIGS. 1-4 of the present invention is the provision of a trailing blade 41 which is behind leading blade 26 in the direction of rotation of the bit. Trailing blade 41 originates at a point 42 on the outer edge 28 of the leading blade which is approximately one-half the distance down from upper end 13. The outer edge 40 of trailing blade 41 diverges from the outer edge 28 of leading blade 26 and the angle of divergence increases proceeding downwardly to a maximum of about 15°. When the bit is new, the outer edge 40 of the trailing blade 41 is slightly closer to axis 14 than the corresponding edge 28 on the leading blade measured in a plane perpendicular to axis 14 to provide "rake." The outside edge 40 of the trailing blade connects with and terminates at the outer corner 36 of the cutting edge 28 of the opposite primary blade 26, and thus reinforces said corner 36. The groove 46 between leading blade 26 and trailing blade 41 is approximately V-shaped and with a radius at the bottom of the V, and the depth of groove 46 increases proceeding downward. The cross-section of secondary blade 41 is similar to that of the primary blade 26.

Thus, each side of the bit consists of two blades 26 and 41 which, proceeding toward the bottom of the bit, are oppositely divergent, the trailing blade 41 veering off toward the opposite leading blade 26.

The horizontal cutting edge 34 of each leading blade, which takes the shock of impact in hard ground, is reinforced by reason of the fact that the outer corner 36 of the leading blade 26, is connected to the outer corner of the trailing blade 41 of the opposite side of the bit. On the other hand, the leading blade side edge 28 is followed in the direction of the rotation of the bit by the outer edge 40 of the trailing blade which is, when the bit is newly manufactured, only a slight distance less from the axis than that of the leading blade. As the bit wears, the outer edge 28 of the leading blade wears away and part of the cutting action is assumed by the outer edge 40 of the trailing blade. Hence, the life of the blades 26 and 41 and the fish-tail ends 12 of the bit are prolonged.

On the forward flank 31 of blade 26 is a plurality of reinforcing ribs 47w-z which are here shown to be four in number but which may be varied depending upon the requirements of the particular bit. As here shown, the uppermost rib 47w originates at origin 48w of the forward edge of upper end 13 adjacent but spaced inward of corner 27 and extends downward along the leading face 31 of blade 26 almost straight down so that it intersects edge 28 at terminus 49w about four-tenths of the overall height of the bit down from upper end 13.

Next uppermost rib 47x originates at origin 48x at radius 33 about one-tenth the vertical height of the bit down from upper end 13. Rib 47x curves from origin 48x at a lesser angle than spiral edge 28 and intersects edge 48 in terminus 49x below point 42 and about six-tenths of the height of the bit below end 13, terminus 49x being horizontally approximately opposite the apex of upper body 11.

Third rib 47y has its origin 48y at radius 33 about opposite terminus 49w (about four-tenths of the height of the bit). Rib 47y curves downward about parallel to rib

47x and its terminus is about coincident with corner 36.

Fourth rib 47z has its origin 48z in radius 33 about opposite terminus 49x and curves across the trailing flank of the opposite trailing blade 49, intersecting edge 40 thereof about one-tenth the height of the bit up from edge 34.

Termini of ribs 47w, x and y are spaced apart approximately equidistantly along the length of edge 28.

Each rib 47 in cross-section is triangular and is of substantially uniform dimension throughout its length except at the extreme lower and upper ends thereof. Ribs 47w-z may be fabricated of hard metal or may be homogeneous. If of hard metal, a preferred method of fabrication is hard facing. The parent metal is heated to a red heat, and the leading surface is bombarded with a hard-face powder. Such a method is described in U.S. Pat. No. 2,361,962 of Wall Collmonoy Corporation, and the equipment for performing the operation is sold by the said company under the trademark "Colomoray Spraywelder." Alternatively, hard-facing rods may be welded on to the leading surface as is well understood in the hard-facing art. It is not intended that the invention be restricted to any particular means or method for forming the rib, and, indeed, the rib may be case of the same metal as the blade.

As the blade 26 wears, the metal between the reinforcing ribs 47w-z wears away. This results in the outer edge 28 of blade 26 between ribs wearing away in indentations leaving protruding fingers at the lower ends 30 of the reinforcing ribs. The fingers augment the cutting action of the bit in that they, for practical purposes, comprise a plurality of digging points which are more effective in breaking down the structure of the soil being drilled than a single continuous blade. It is, of course, true that the reinforcing ribs even when hardened eventually wear, but being thicker than the blade edge, they wear at a slower rate than the body 11.

A principal additional function of the reinforcing ribs 40 is to strengthen the blades against the impact of the bit striking a hard rock. There is a tendency for the blade to be broken off on such impact. This is particularly true of the fish-tail portions 12 of the blade which project towards the bottom. The reinforcing ribs 47y, z materially strengthen said protruding fish-tails, which are inherently the weakest part of the blades as they normally strike the hard formation first and also are relatively unsupported by the body of the bit. Hence, a primary function of at least one of the reinforcing ribs 47w-z is to strengthen the blades 26 and the fish-tail structure.

The ribs increase the overall life of the bit since they reduce wear and absorb a substantial amount of the wear of the bit particularly after the initial wearing of the indentations 43 between the fingers 44. The reinforcing ribs 41, 42 also enable the bit to cut through a harder formation than would normally be the case. Ordinarily pilot bits of the type shown in U.S. Pat. No. 2,773,673 are not suitable for digging through rock, but the present pilot bit will bore through rock at least if the rock is not too hard.

In the form of the invention shown in FIGS. 5-8, on the leading flank 31a of leading blade 26a (in the normal direction of rotation of the bit, which is counter-clockwise as viewed in FIG. 6), a first reinforcing rib 51 is formed commencing at the outer corner 36a of cutting edge 34a and extending substantially straight upwardly on said leading flank parallel to the axis of rotation.

tion 14 to a terminus 52 about one-half the overall height of the bit up from edge 34a. Said rib 51 in cross-section (see FIG. 8) is triangular and is of substantially uniform dimension throughout its length except at the extreme lower and upper ends thereof. Rib 51 may be fabricated of a hard metal or may be homogeneous, as is the case with ribs 47w-z.

In the form of the invention shown in FIGS. 9-11, a modified construction is shown. In this version of the invention, a trailing blade 41b is located behind the leading blade 26b in the direction of rotation of the bit, as in FIGS. 1-4. No reinforcing ribs corresponding to ribs 47w-z are employed. However, a reinforcing rib 51b is formed on the leading face of the fish-tail 29b of the leading blade 26b. The position and shape of rib 51b corresponds to rib 51 of FIGS. 5-8.

In other respects, the modification of FIGS. 5-8 and FIGS. 9-11 are substantially the same as in the modifications of FIGS. 1-4 and the same reference numerals followed by the subscript *a* and *b* respectively, are used to designate corresponding elements.

What is claimed is:

1. A pilot bit for an earth auger comprising a body having a top, said body having an upper portion which is of an approximately inverted triangle shape in side elevation viewed in one direction and narrower and substantially rectangular viewed rotated 90° and having blades at angularly spaced positions on the exterior of said body, each said blade originating at said top and extending downwardly in spiral shape of about 180° arcuate length on the outside of said body, each said blade having a leading face and a trailing face in the normal direction of rotation of said bit when said bit is digging in the earth, the projection of said blade outward gradually increasing as said blade extends downward, said blade extending below the apex of the triangle of said body in a fish-tail and formed with a cutting edge parallel to, but spaced outward of, a diameter of said body, and a plurality of reinforcing ribs on said leading face of said blade, each said rib having an origin spaced inward of the outer edge of said blade and formed in a downwardly curving spiral and having a terminus on said outer edge.

2. A bit according to claim 1 in which each said rib is approximately triangular in cross-section.

3. A pilot bit according to claim 1 in which said body is formed with secondary blades on the exterior of said body, each said secondary blade originating on the outside edge of one of said first-mentioned blades partway down from said top, each secondary blade of spiral shape and gradually diverging at an angle rearward of said first-mentioned blade to which it is connected and increasing in projection from said body as said secondary blade extends downward and also increasing in distance behind said first-mentioned blade as said blades

extend downwardly, said secondary blade extending below the apex of said body in a secondary fish-tail which joins at its bottom end with the outer corner of the cutting edge of the first-mentioned fish-tail of the first-mentioned blade opposite that to which said secondary blade is connected, said reinforcing ribs being located on the leading face of said first-mentioned blade.

4. A bit according to claim 1 in which said one rib has its terminus on said cutting edge of said fish-tail.

5. A bit according to claim 4 in which another of said ribs is on the leading face of one said fish-tail and has its terminus on the trailing face of the next blade.

6. A pilot bit for an earth auger comprising a body having a top, said body having an upper portion which is triangular in side elevation viewed in one direction and narrow and substantially rectangular viewed rotated 90° and having blades at angularly spaced positions on the exterior of said body, each said blade originating at said top and extending downwardly in spiral shape of about 180° arcuate length on the outside of said body, each said blade having a leading face and a trailing face in the normal direction of rotation of said bit when said bit is digging in the earth, the projection of said blade outward gradually increasing as said blade extends downward, said blade extending below the apex of the triangle of said body in a fish-tail and formed with a cutting edge parallel to, but spaced outward of, a diameter of said body and a hard triangular reinforcing rib on said fish-tail extending up from said cutting edge centrally of the leading face of said fish-tail about one-half the overall height of said bit.

7. A pilot bit according to claim 6 in which each said reinforcing rib is of approximately triangular cross-section.

8. A pilot bit according to claim 6 in which said body is formed with secondary blades on the exterior of said body, each said secondary blade originating on the outside edge of one of said first-mentioned blades partway down from said top, each secondary blade of spiral shape and gradually diverging at an angle rearward of said first-mentioned blade to which it is connected and increasing in projection from said body as said secondary blade extends downward and also increasing in distance behind said first-mentioned blade as said blades extend downwardly, said secondary blade extending below the apex of said body in a secondary fish-tail which joins at its bottom end with the outer corner of the cutting edge of the first-mentioned fish-tail of the first-mentioned blade opposite that to which said secondary blade is connected, said reinforcing rib being located on the leading face of said first-mentioned blade.
